UNITED STATES PATENT OFFICE

GERALD DEAKIN, OF NEW YORK, N. Y., AND LIPA POLINKOWSKY, DECEASED, LATE OF PARIS, FRANCE, BY EDOUARD FRUM, ADMINISTRATOR, OF PARIS, FRANCE, AS SIGNORS TO INTERNATIONAL STANDARD ELECTRIC CORPORATION, OF NEW YORK, N. Y.

AUTOMATIC AND SEMIAUTOMATIC TELEPHONE EXCHANGE SYSTEM

Application filed May 18, 1930, Serial No. 452,083, and in Great Britain May 14, 1929.

This invention relates to machine switching telephone systems and more particularly to systems wherein in addition to the ordinary service provided for the interconnection 5 of the subscribers' lines, means is provided for extending connection to subscribers' lines from a toll operator's position or a wire chief's testing board.

A particular object of the invention is the provision of such facilities in an automatic or semi-automatic telephone system of the kind in which the conversation switches at the numerical switching stages are operated under the control of control circuits each common to a plurality of conversation switches but individual to one switching stage.

According to the invention in a system of the above type, the same final conversation switches are used for extending ordinary calls and toll calls means being provided in the common control circuits associated with the final conversation switches whereby different operations of the latter for completing the two types of connection are brought about.

According to a further feature of the invention in a system of the above kind, conversation switches are provided for setting up both ordinary connections and toll connections, common control circuits associated therewith being provided with means for exercising a discrimination whereby in the case of an ordinary connection ringing current is automatically applied to a wanted line but in the case of a toll call a connection is completed to a wanted line without such automatic application of ringing current.

According to still a further feature of the invention in an automatic or semi-automatic telephone system in which means is provided for setting up toll calls and in which the conversation switches at the numerical switching stages are operated under the control of control circuits each common to a plurality of conversation switches but individual to one switching stage, the same conversation switches are employed for extending both ordinary and toll connections.

According to yet another feature in a system of the kind referred to above, special 50 conversation switches are provided for set-

ting up preferred calls, for example, calls from a toll offering operator's position or a wire chief's testing board, such special conversation switches being adapted to be operated under the control of control circuits 55 which are also adapted to control the operation of the conversation switches employed in extending ordinary calls.

These and other features specified in the appended claims will be better understood 60 from the following description taken in conjunction with the accompanying drawings in which the invention is described as applied to a system using single motion power driven switches for both the conversation 65 switches and the control circuit steering switches.

Referring now to the accompanying drawings:

Fig. 1 shows a subscriber's line and starting circuit and a first line finder.

Fig. 2 shows a second line finder circuit.

Fig. 3 shows a first group finder circuit.

Fig. 4 shows a second group finder circuit.

Fig. 5 shows a final finder circuit.

Fig. 6 shows a first group finder control circuit.

Fig. 7 shows a second group finder control circuit.

Fig. 8 shows a final finder control circuit.

Fig. 9 shows a register circuit including a register finder.

Fig. 10 shows an incoming two-wire junction relay set.

Fig. 11 shows a special service operator's position.

Fig. 12 shows a toll junction equipment and (in the left-hand top corner) a toll board cord circuit.

Fig. 13 shows a toll offering and wire chief testing junction equipment and (in the left-hand top corner) a toll board cord circuit and wire chief's position in skeleton.

Fig. 14 shows a toll offering and wire chief's testing final finder circuit.

Fig. 15 is a layout diagram of a typical system.

A general description will first be given with reference to Fig. 15.

When the telephone is removed from the hook at substation S the calling line is extended over first and second line finders LF1, LF2, to a first group finder 1GF having an 5 idle associated control circuit 1CF. Immediately thereafter the line finder circuit comprising the second line finder LF2 and group finder 1GF is attached to an idle register circuit RC over a register finder PR, 10 whereupon dialling tone is sent to the calling party.

The subscriber dials in the usual way. The first digit dialled advances the first digit switch in the register circuit to the corresponding position. When the first digit has 15 been received a signal is sent forward from the register circuit to cause the first group finder switch 1GF associated with the line finder LF2 to become connected with its associated control circuit the finder switch 1CF of which is set in rotation and hunts until it finds the first group finder switch 1GF. The control finder 1CF is then further advanced to a position corresponding to the 20 first digit dialled in which position it marks the wanted group of trunks outgoing from the bank of the switch 1GF: during the last-mentioned movement revertive impulses are sent back from the control finder 1CF to 25 count out the first digit switch in the register circuit RC. The first group finder 1GF is now caused to hunt for a free trunk extending to a second group finder 2GF the associated control circuit of which is idle, in the 30 group determined by the setting of the control finder 1CF. It should be noted that the trunks from the arcs of the group finder switches need not be arranged in definite order and further the groups may not contain the same number of trunks. Whenever 35 it is found necessary to increase the number of trunks in a particular group this can be done without disturbing the existing connections, the additional trunks being connected 40 to any spare positions in the arcs.

The further extension of the connection depends upon the type of call which is being set up. We will assume for the time being that the call in progress is a local one. When 50 the second digit has been dialled, a signal is again sent forward from the register circuit RC to cause the second group finder 2GF which has been taken for use to become attached to its control circuit, the finder 2CF of which is set in rotation and hunts until it finds the engaged second group finder 2GF. The control finder 2CF is then further advanced to a position corresponding to the second dialled digit, to mark a wanted group of 55 trunks in the bank of the finder 2GF, during this movement revertive impulses being sent back to the register circuit to count out the second digit switch therein. The second group finder 2GF is now caused to hunt in 60 the wanted group for a free trunk to an idle

final finder FF the associated control circuit of which is also idle.

When the third or tens digit and at least one impulse of the fourth or units digit have been received by the register circuit, the control circuit of the final finder FF is taken into use and its finder FCF hunts until it finds the final finder FF. The control finder FCF then advances further to a position corresponding to the tens digit during this 75 movement revertive impulses being sent back to count out the tens digit switch. The final finder FF now advances to the wanted group after which the control finder FCF continues to advance to a position corresponding to the wanted line; during this movement the final finder FF follows the control finder FCF and a revertive impulse is sent to the units digit switch for each position through which the switch FCF is advanced. 80

In addition to controlling tens and units selection the final control circuit determines whether or not the called member is an individual line or a P. B. X. group. Provision is made for P. B. X. hunting by providing 90 the cut-off relays of all the lines of a P. B. X. group excepting the last line with an additional contact over which an engaged potential is applied to a corresponding terminal in the arc of the control finder FCF when the 95 line is busy. In case the called number corresponds to a P. B. X. group and the first line is found busy, the control finder FCF causes the advance of the final finder FF until a free line is found. In case all the 100 lines of the group are found busy the usual busy tone is sent to the calling line.

It should be noted that the control circuits are not engaged until the register circuit is ready to receive the corresponding revertive impulses. By this means the control circuits are held in use for the shortest possible time. In case all the trunks of a wanted group are busy the group finder switches are arranged to continue hunting 110 for a predetermined time, say 10 seconds. If a free trunk is not found within this time the register circuit frees the control circuit and applies busy tone to the calling lines.

It will also be seen that a control circuit 115 finder has a dual function. It first advances from a normal position and causes the attachment of a predetermined trunk and an associated group or final finder switch to the control circuit and afterwards it controls the setting of the group or final finder. For example, there are usually ten trunks and their associated finders in a group served by one control circuit. If trunk No. 6 has been selected from a preceding switching stage, the control circuit finder advances and when position six is reached this trunk is attached. The control finder then continues to advance and sends back the revertive impulses. 120

All the switches in the talking circuit are 125

of the non-homing type and on release of the connection remain in the positions to which they were last set.

The register circuit RC is arranged to handle two-digit special service calls for which the numbers 01, 02 etc., are reserved. Such calls are extended to an operator's position OP over a regular first group finder, such as 1GF, and a special second group finder such as SGF controlled by a control finder SCF. The transmission bridge at the line finder circuit LF2, 1GF is removed on such calls and the calling line is connected metallically to the manual cord circuit from which battery for talking is supplied. Such a connection remains under the control of the operator and the automatic subscriber cannot release until the operator takes down the connection.

False calls are also automatically extended to a similar operator's position over two group selecting stages. The number "00" is assigned to false calls the register circuit being automatically set to these digits by grounded lines or failures to dial within 30 seconds. When a false call is extended the current bridge is automatically removed from the line finder circuit so as not to heat the bridge relay. The operator by depressing a key can flash a guard lamp of the line finder circuit LF2, 1GF, to indicate the finder held by the false call.

For extending toll calls from toll operators' positions TB, toll junctions are provided which incorporate relay groups TR and terminate in special first group finders TGF. When a toll junction is taken for use it becomes connected to a regular register circuit RC. The group finders TGF are similar to the regular second group finders 2GF. The same second group finders 2GF and final finders FF are used for extending these calls, but when taken into use from a toll junction circuit TR the register circuit RC is arranged to exercise a discrimination whereby the final finder FF suppresses ringing current so that the calling of the wanted party is entirely under the control of the toll operator. If the wanted line is engaged the toll operator receives the regular busy tone.

Toll offering boards TOB and wire chief testing boards WCB are provided for obtaining access to junctions incorporating relay groups TOR and terminating in first group finders TWGF. When a junction is taken for use it becomes connected to a regular register circuit RC. A special train of first and second group and line finder switches TWGF1, TWGF2, TWFF is employed for extending such connections. These first and second group finders TWGF1 and TWGF2 are identical with the regular second group finders 2GF but they are not connected to the same multiple as the regular group finders. The toll offering first group finders TWGF1 are controlled by the same control

circuit TCF as the toll first group finders TGF whilst the toll offering second group finders are controlled by the same control circuit 2CF as the regular second group finders 2GF. To each group of 100 subscribers' lines one toll offering and testing final finder TWFF is provided which differs from the regular final finders FF in that it is arranged to stop on the wanted line without testing or ringing. These finders TWFF are adapted to be controlled by the same control circuits FCF as the regular final finders FF.

Two-wire junctions IJ from distant offices terminate in relay groups IJR and incoming group finders JGF controlled by control circuits comprising control finders JCF. These group finders and control circuits are identical with the local group finders 2GF and their control finders 2CF. The relay group IJR incorporates a transmission bridge which is arranged to be cut out and a clean metallic circuit substituted therefor during the setting up of a connection.

Typical calls will now be traced out in detail:

Local call

On a subscriber removing his receiver to make a call the line relay Lr, Fig. 1 is energized over the calling loop. Relay Lr places a battery potential on the first line finder test multiple d and closes a circuit for a common starting relay Fsr which energizes starting relays Asr. Relays Asr close circuits for the clutch magnets PF, of all free first line finders in series with relay LgL via contacts Ltr2, Lhr3. If there are no free finders in the group relay Lgr remains de-energized and a guard lamp LGL lights.

When a finder, say the one illustrated, reaches the calling line, test relay Ltr operates over its high resistance right-hand winding, opens at contacts Ltr2 the circuit of magnet PF and at contacts Ltr1 closes a circuit for relay Lhr over its right-hand winding and the common starting relay Csr of a sub-group of second line finders. Relay Ltr also connects battery to the second line finder test multiple d. Relay Lhr at contacts Lhr1 connects the low-resistance left-hand winding of relay Ltr in parallel with its high-resistance winding to cause the relapse of relay Lr which de-energizes the relays Asr to all the remaining first line finders. The group of second line finders is divided into four sub-groups, the arrangement being that only the free finders of one sub-group are set in rotation for one originated call, but in the event of all the finders in this sub-group being engaged, the free finders of the next sub-group are set in rotation and so on:

The relay Csr of the first sub-group energizes on auxiliary relay Hsr which energizes one or more starting relays Bsr of the sub-group and prepares a circuit for the auxiliary

- relay H_{sr} of the next sub-group. The relays B_{sr} and H_{sr} close parallel driving circuits for the free finders of the first sub-group over a common relay S_{gr} . If no finders are available in this sub-group the slow-acting relay A_{br} will be energized and close the circuit of the C_{sr} relay and relay H_{sr} of the second sub-group in which free finders will be started by the energization of the B_{sr} relays. It will be easily understood from the circuit that if no finders are free in the second sub-group, the third sub-group starting relays will be operated and so on until all the four sub-groups are in action. If no finder is free in the whole group, a supervisory lamp SGL is lighted over a circuit extending over front contacts of the A_{br} relays of the last three sub-groups.
- The pilot relay S_{gr} is adjusted to operate over a single driving circuit. If desired it may be so adjusted that it does not operate unless two, three, etc. driving circuits are closed, in which case a second sub-group is started if only two, three etc., finders are available in the first sub-group.

In the second finder illustrated in Fig. 2 the driving magnet PL is energized in a circuit extending over contacts Ar_1 , Fr_1 , Gr_3 , and Dr_2 . When a second line finder has picked up the first line finder, the test relay Ar operates over its high-resistance left-hand winding to ground at contacts $1Ec_1r_1$ in the control circuit, Fig. 6 serving the first group finder, Fig. 3 linked to the second finder. If the control circuit, Fig. 6 is operatively associated with another group finder, the relay $1Ec_1r$ will be energized as described subsequently no circuit will exist for the test relay Ar , and another second finder will pick up the engaged first finder.

Relay Ar opens the driving circuit at contacts Ar_1 and closes the following circuit for relay Cr ground winding of relay S_{gr} , Fig. 1, contacts Ar_2 , right-hand winding of relay Cr and contacts Dr_7 to battery. Relay Cr at contacts Cr_1 connects the low-resistance right-hand winding of relay Ar in parallel with its high-resistance winding causing the relapse of relay C_{sr} , Fig. 1 provided there is no other call existing at this instant in the same group. Relay Cr also at contacts Cr_2 closes a circuit for relay Br which energizes the relay Dr in a circuit over contacts Br_1 , Gr_7 , Fr_6 : a locking circuit is now closed for relay Cr via contacts Cr_3 , Er_3 and the make before break contacts Dr_6 — 7 . Relay Dr at contacts Dr_4 connects ground to the third wire c causing the operation of the cut-off relay Cor , Fig. 1, over the left-hand low-resistance winding of relay L_{hr} which remains operated in this circuit. Relay Cor disconnects the line relay L_{tr} which opens the circuit of relay L_{tr} . Meanwhile the relay C_{sr} has de-energized and opened the cir-

cuit of the relays H_{sr} , B_{sr} thereby stopping further hunting.

Relay Dr at contacts Dr_1 , Dr_3 connects the supervisory relay Sr across the calling loop and at contacts Dr_7 — 6 connects battery via contacts Cr_4 to the leads 1 and 2 to energize the register starting circuit relays Arr , Fig. 9, and to apply test potential to the test contacts in the banks of the register finders. Relay Br is now held over contacts Sr_2 of relay Sr .

The register starting relays Arr energize starting relays Brr which close circuits for the clutch magnets PR of register finders associated with free registers: in the register circuit shown this circuit extends from battery, over magnet PR , contacts Grr_4 , Err_3 , Brr_3 , Crr_1 , to ground. The test relay Crr of the first finder which reaches the engaged second finder circuit energizes over its left-hand high-resistance winding via contacts Drr_1 , normal contacts and brush a of the units register, normal contacts and brushes d of the remaining digit registers and ground, opens the circuit of magnet PR and closes a circuit for relay Err . Relay Err shunts the high-resistance winding of relay Crr with its right-hand low-resistance winding at contact Err_1 , lights a busy lamp BL at contacts Err_1 — 2 , opens a further point in the circuit of magnet PR at contact Err_3 and at contacts Err_6 and Err_7 connects dialling tone to the calling line. The dialling tone circuit extends from the right-hand winding of the tone transformer TC , small condenser MF_1 , contact Rr_6 , windings of relay Pr , contacts Err_6 , register finder wiper b , contact Er_2 , Fig. 2, b wire bridge condenser, calling loop, a wire bridge condenser, contact Er_1 , register finder wiper a , Fig. 9, contact Err_7 back to the tone transformer winding. The circuit of the primary winding of the transformer TC is completed via dial tone lead D , contacts Frr_2 , Err_4 — 3 , Grr_4 and the winding of magnet.

The calling party now dials the first or thousands digit of the wanted number, thereby intermittently opening the circuit of relay Sr , Fig. 2, which at each relapse closes an impulse circuit for relay I_{tr} and H_r , Fig. 9, via contacts Sr_1 and Er_5 . The relay Br , Fig. 2 is of the slow-releasing type and during impulsion remains operated. At each energization of the impulse relay H_r a circuit is closed over contacts H_r_2 , Jr_3 for the stepping magnet SW_1 of the first digit register. Relay I_{tr} energizes on the first impulse and being of the slow-to-release type remains operated during impulsion. As soon as the first digit register reaches the first terminal set the following circuit is closed for relays Er , Fig. 2 and Ur , and Vr Fig. 9:—battery, contacts Dr_7 — 6 , Fig. 2, lower winding of relay Er , register finder brush c , Fig. 9, contacts Frr_1 , low resistance right-hand winding of relay

Ur, winding of relay Vr, off-normal arc and brush b of first digit register, contacts Drr6, to ground. Owing to the high-resistance of relay Er relay Vr does not operate in this circuit. A locking circuit for these relays is closed via contacts Ur3 and Drr6.

Relay Er, Fig. 2, disconnects the dial tone, and at contacts Er3 opens the locking circuit of relay Cr, which removes the test potential 10 from the contact engaged by brush d of the register finder, thereby de-energizing relay Crr, Fig. 9. Relay Err Fig. 9 however remains held via contacts Ur2. At the end of 15 the first impulse series relay Jr relapses and closes a circuit for relay Jr via brush a of the first digit register. Relay Jr closes a circuit for slow-acting relay Grr via its contact Jr6 to ground locks over contacts Jr5, Err2-1, and at contact Jr4 transfers the impulsive 20 circuit via contact Lr3 to magnet Sw2 of the second digit register.

When the subscriber sends the second series 25 of impulses the magnet Sw2 of the second digit register responds and the register takes up a position corresponding to the digit dialled. On the cessation of these impulses relay Lr becomes energized and transfers the impulsive circuit to the magnet SW3 of the third digit register over contacts Lr4, Tr6, 30 Or6. The third series of impulses advance this register and when the last impulse is received relay Or energizes and transfers the impulsive circuit via contacts Or5 to the magnet SW4 of the last digit register which 35 responds to the last series of impulses.

On the response of relay Jr at the end of the first impulse series the following circuit is also closed for relay Kr:—ground, contacts Jr6, Grr2 left-hand winding of relay Kr contacts Frr6 to battery: relay Kr locks over contacts Kr2, Nr1, Err2-1 independently of contacts Jr6 and Grr2. Relay Kr connects ground to the b wire of the fundamental circuit via contact Kr4, winding of the outstepping relay Pr, contacts Err6, and the register finder brush b, and connects battery to the a wire of the fundamental circuit via a resistance, contacts Kr3 and the register finder brush a.

50 The connection of battery to the a wire closes a circuit for the common starting relay Acr, Fig. 6 of the first group finder control circuit via contacts Cr5, Fig. 2 and J2r2, Fig. 3 and places a potential on the contact of the level wiped over by brush i particular to the engaged first group finder.

It will be convenient here to describe the arrangement of the bank contacts of the group finder control circuit switches. These 55 have 51 points or positions (the first being used as a home position) and five levels of contacts wiped over by brushes f-j. The ten contacts in the first ten positions in levels h and i are wired to the ten group finders usually controlled by one control circuit.

The remaining 40 points in these two levels are not used. Points 11 to 50 are used for the reverting control and in levels f and g are divided into ten groups of four each. In level g the second and third contacts of each group of four are strapped together and grounded. The fourth contact of each group of four in level f is wired to the marking terminals d of its corresponding group of junctions outgoing from the group finder switches. The marking wires are connected to terminals f1, f2, f3 etc. on a small terminal strip from which jumpering wires are taken to the group finders. The 100 outgoing trunks, the normal capacity of the group finders, may be divided into ten groups of different sizes, providing the total remains 100: The d terminals of all the trunks of the first group are wired to the first terminal in level f of the control switch, all those of the second group to the second f terminal and so on. All the trunk groups may comprise 80 10 trunks each or some groups may be larger and others smaller. As the group finders have no home positions, the junctions in each group may be distributed in any order around the arc so as to reduce hunting. Where ten trunk groups are not required the finder arcs may be divided into fewer groups. For example, assuming a network involving 90 an ultimate capacity of four offices, the first group finder arc might be divided into 5 groups, say, one of 25 for junctions to the most distant office, 2 of 20 for junctions to the remaining distant offices, one of 25 for local calls, and one of 10 to a group of special service finders. The contacts in the level j are grounded and are used for centering the brushes.

Resuming now the operation of the system, the starting relay Acr Fig. 6 when energized 105 closes a circuit over contacts Fcr2 and Ber1 for the power magnet PC and the control finder switch is rotated. A circuit is also closed for relays Ecr which remove earth from the left-hand windings of the test relays Ar, Fig. 2 of all the second finders linked with the first group finders served by the control circuit in order to prevent any of these 110 second finders from picking up a first finder whilst the control circuit is in use. When the calling trunk is reached, the test relay Ber operates to the battery on the test contact, the power magnet P. C. is disconnected and the following circuit is closed for relays Fcr, Fig. 6 and J1r, Fig. 3:—battery, windings of relays Fcr and J1r, contacts and wiper of level h, contacts Ber2, Fcr2, off-normal contacts N to ground. Relay Fcr is slow-to-operate. Relays Fcr and J1r lock to ground at contacts Br1, Fig. 2, via contacts J1r3, J2r1, and the c wire, and at contacts J1r1 connects the b wire of the fundamental circuit to relay Der of the control circuit. The outstepping 120 relay Pr in the register Fig. 9 now energizes 125 130

in series with relay Dcr , Fig. 6. Relay Pr closes at contacts $Pr2$ a circuit via contacts $Mr4$ for relay Rr , which locks to ground over its contacts $Rr4$, and wiper c of the first digit 5 register and contacts $Err2-1$, providing that the switch is in one of the positions 1 to 9. This locking circuit is not closed if the switch is in position 10. Relay Rr closes an obvious circuit for relay Nr and at contact 10 $Rr5$ connects the outstepping relay Pr in a metallic circuit across the a and b wire of the fundamental circuit. Relay Ber Fig. 6 now relapses being unable to remain operated in series with relay Dcr . Relay Nr at contacts 15 $Nr1$ opens the locking circuit of relay Kr . In the control circuit relay Dcr closes the following circuit for the power magnet PC of the control finder switch:—ground, off-normal contact N , contacts $Fcr1$, $Dcr1$, $Gcr3$, 20 winding of magnet PC to battery. The control switch now advances its brushes over the remainder of the ten calling junction positions and in its further advance each time the brush g passes over a grounded group contact 25 the outstepping relay Pr of the register is short-circuited for an instant. At each relapse of relay Pr a circuit is closed via contact $Pr1$ and $Rr4$ for relay Qr which closes a circuit via contact $Qr2$ and brush f of the 30 first digit register for the magnet $SW1$ thereof and locks up via contact $Qr1$ and brush e of this register to the grounded interrupter contacts I of the magnet $SW1$, thus maintaining the circuit of magnet $SW1$ closed 35 even if relay Pr should open its back contact before magnet $SW1$ is fully energized. In this manner the first digit register is advanced until it reaches position 10 in which the locking circuit of relay Rr is opened. At 40 the next de-energization of the outstepping relay Pr , relay Rr relapses and at contact $Rr5$ opens the fundamental circuit. Relay Nr is now deprived of current, but being of the slow-to-release type remains on its front 45 contact $Nr2$ long enough to cause the energization of relay Srr via contacts $Rr1$ and $Err2-1$. Relay Srr closes the following circuit for relays Mr and Qr :—ground contacts $Err1-2$, $Nr2$, $Srr1$ brush c of first digit 50 register, left hand winding of relay Mr and winding of relay Qr to battery. Relay Qr recloses the circuit of magnet $SW1$ which advances the first register to its normal position whilst relay Mr recloses the fundamental circuit 55 at contact $Mr5$ and locks over its right-hand winding via contacts $Frr6$, $Mr3$ and $Pr2$. If the first digit register is set by dialled impulses to position 10 the relay Rr relapses on the first de-energization of the 60 outstepping relay Pr and the operation proceeds as described above.

During the opening of the fundamental circuit at the register between the relapse of relay Rr and the response of relay Mr , relay 65 Dcr , Fig. 6, in the finder control circuit de-

energizes and closes a circuit for relay Gcr extending from ground at off-normal contacts N via contacts $Fcr1$, $Dcr2$ and $Gcr1$. Relay Gcr locks over contacts $Gcr1-2$ and connects ground via contacts $Gcr5-4$, the high-resistance right-hand winding of test relay Hcr , brush f and the engaged marking terminal, to all the d terminals of the group of trunks corresponding to the first digit dialled by the subscriber. The power magnet PJ of the group finder also receives ground over contacts $Gcr5$, $Hcr1$, and $J1r4$, and the group finder rotates. As its brushes c and d are connected together over contacts $J1r6$, when a trunk in the wanted group is reached at which both the group finder and associated control switch are idle the test relay Hcr in the control circuit energizes from the battery connected to the c wire of the trunk over contacts $2Ecr1$, Fig. 7. Relay Hcr connects a low-resistance test relay Scr and its own low-resistance left-hand winding in parallel with its high-resistance right-hand winding thereby busying the seized trunk to other calls. Relay Scr closes a circuit via contacts $Scr1$ and $J1r5$ for the group finder relay $J2r$ which locks to the grounded front contact $B1r$ of relay Br Fig. 2 in the line finder circuit. Relay $J2r$ completes at 95 contacts $J2r3$ and $J2r4$ the through connection from the line finder circuit to the seized trunk and opens at contacts $J2r1$ the locking circuit of relay $J1r$ which releases thus disconnecting the group finder from the control circuit. Relay Fcr is also deprived of current when relay $J2r$ energizes, opens the holding circuit for relay Gcr and closes a restoring circuit for the control switch over the off-normal contact N and contacts $Fcr2$ and $Bcr1$. If the relay Acr is energized due to another trunk being in a calling condition; the switch will continue rotating and the second trunk will become immediately attached.

Returning now to the register, when the relay Lr energizes after the recording of the second or hundreds digit, a further circuit is closed for relay Kr which extends from battery, left-hand winding of relay Kr , contact $Lr6$, brush b of hundreds digit register, and contacts $Mr1$, $Nr1$, $Err2-1$ to ground. Relay Kr re-connects battery to the a wire and energizes the starting relay $2Acr$, Fig. 7 of the control circuit of the second group finder, and reconnects ground through the outstepping relay Pr to the b wire. It will be seen therefore that if a second group finder is taken into use before the hundreds digit has been completely recorded, the control circuit is not attached until the register is ready to receive the reverting impulses. On the other hand if the register becomes ready to receive the reverting impulses before a second group finder has seized or before a control circuit has become attached to a seized 125 130

second group finder, relay K_r will be re-energized immediately relay M_r relapses when the fundamental circuit is opened on the first group finder engaging a free junction with the aid of its control circuit, and will therefore cause the attachment of a second group finder control circuit at the earliest possible moment.

A second group finder is shown in Fig. 4 and its control switch in Fig. 7 but since its control circuit is similar to that illustrated in Fig. 6 it is only necessary to describe briefly the operations at the second group selecting stage. The starting relay $2A_{cr}$ closes a circuit for the control circuit driving magnet $2PC$ which advances the control switch wipers to the calling trunk on which magnet $2PC$ is de-energized and the group finder relay $2J1r$ energizes in series with the control circuit relay $2Fcr$. Relay $2J1r$ attaches the control circuit. The register outstepping relay P_r now energizes in series with the control circuit relay $2D_{cr}$ over the b wire of the fundamental circuit, the control switch is again rotated and reverting impulses are sent back to the register circuit to count out the hundreds register switch. The fundamental circuit is then momentarily opened at the register circuit, the control circuit relay $2D_{cr}$ de-energizing and energizing relay $2G_{cr}$, which connects up the test relay $2H_{cr}$ and closes a circuit for the group finder power magnet $2PJ$. The group finder hunts in the marked group and when a free trunk is found relays $2H_{cr}$, $2S_{cr}$ and $2J2r$ energize, completing the connection to the final finder. Relay $2J2r$ opens the circuit of relay $2J1r$ which disconnects the control circuit. Relay $2Fcr$ relapses and closes a circuit for the magnet $2PC$ which drives the control switch to normal or to another calling trunk. The fundamental circuit is opened and the register relays P_r and M_r de-energize.

Providing that the fourth or units digit register switch has moved to its first position, that is, that at least one unit impulse has been received by the register, a circuit is again established for the relay K_r this circuit extending from battery, left-hand winding of relay K_r , brushes b of the tens and units registers, and contacts M_{r1} , Err_2 —1 to ground. Relay K_r locks up and re-connects battery to the a wire of the fundamental circuit and ground to the b wire through the outstepping relay P_r . The starting relay $3A_{cr}$ Fig. 8 of the final finder control circuit is energized over the a wire of the fundamental circuit and energizes relay $3E_{cr}$ and removes battery from the common lead to busy all the associated trunks as long as the common circuit is in use.

It will be convenient here to describe the arrangement of the bank contacts of the final control circuit switches. These switches have a capacity of 102 points arranged in two semi-

circular arcs of 51 points each. The finders have six sets of brushes as shown. The normal contact N closes whenever the switch leaves its home position and is not opened until the wipers have made a complete revolution through 360° . The lines in the upper and lower levels of P and f are numbered as indicated. The extra positions H and H' in each level are located where indicated.

The two levels P are used as described subsequently for P. B. X. hunting. These two levels are wiped over by two connected single-ended brushes arranged 180° apart, one brush wiping over the upper 51 terminals during the first half revolution and the other brush over the lower 51 terminals during the second half revolution. The terminals in positions H and H' are dead.

The two levels f are wired to the marking contacts d of the final finders and are arranged in the same manner as the levels P .

Level g comprises five wide segments occupying positions 8—9, 18—20, 29—30, 39—40 and 49—50 respectively. These segments are wiped over by a double-ended brush twice during each complete revolution and the grounding of the fundamental circuit takes place over these segments. The segment immediately preceding the position H and H' is one position longer than the others since the brushes have to take an extra step over these contacts to reach the beginning of the next group.

The levels h and i contain 10 terminals occupying positions 1—10 in the first half revolution. These levels are wired to the final finder circuits, there being, therefore, capacity for 10 final finders in each group: this number however may be varied according to requirements. These levels are wiped over by two single brushes and are therefore wiped over but once during a complete revolution of 360° .

Level j consists of a series of grounded terminals wiped over by a double-ended brush. These terminals are used to center the control finder brushes.

As the control finder may pick up a final finder between positions 1 to 10 it is necessary that the segment in positions 8 and 9 in level g be insulated until the brush commences on its second half revolution. The reverting count is therefore commenced on the segment in positions 19—20 and the contacts in levels p and f are numbered accordingly. The first engagement of this segment by brush g causes the energization of relay $3Fcr$, Fig. 8, which grounds the first segment (in positions 8—9) during the remainder of the selective operation.

Resuming the circuit operation, relay $3A_{cr}$, Fig. 8 closes a circuit for the power magnet $3PC$ via contacts $3A_{cr1}$, $3D_{cr3}$, $3F_{cr3}$ and $3B_{cr1}$. The brushes rotate and when the calling trunk terminals are reached

relay 3Bcr is energized over brush *i* and the *a* wire of the fundamental circuit, opens the circuit of the magnet 3PC and completes the following circuit:—ground, off-normal contacts N, contacts 3Dcr3, 3Fcr3, 3Bcr2, brush *h*, windings of relays F1r and F3r in parallel, and contact 3Fcr8 to battery. The marginal relay F3r does not operate but relay F1r energizes locks over contacts F1r3, F3r6, 5 F2r1 and the *c* wire to grounded contacts 2J2r1, Fig. 4, and closes a circuit over contacts F1r1 and the *b* wire of the fundamental circuit for the outstepping relay Pr in the register circuit and for relay 3Dcr in the control circuit. Relay 3Dcr recloses the circuit of the power magnet 3PC via contacts 3Gcr1 and 3Dcr2. When the brush *g* engages the first grounded group contact in positions 10 18—20 a circuit is closed over contacts 3Gcr7, 3Dcr1 and 3Fcr1 for relay 3Fcr which locks over contacts 3Fcr7—8 in series with relay F1r, Fig. 5, connects the brush *g* to the *b* wire of the fundamental circuit via contacts 3Gcr7, 3Dcr1 and 3Fcr2, and grounds the 15 first reverting group contact and the centering contacts in level *j* via contacts 3Ecr3, and 3Ecr2. As will have been appreciated from the preceding description this group contact occupies positions in the arc allotted to the 20 calling trunks and the sending of reverting impulses must not begin until after the control switch has passed beyond this group in order that the first reverting impulse shall always be sent back from the same position on the control switch arc no matter whether the first or last final finder is selected. The 25 control switch continues to rotate and for every ten steps a reverting impulse is sent over the *b* wire to count out the tens register in a similar manner to that previously described with reference to the thousands register.

In the register circuit when the tens register arrives in position 10, on the next relapse of relay Pr relay Rr falls away and opens the fundamental circuit. Relay Rr opens the circuit of relay Nr and between the relapse of these two relays relay Srr is energized and closes the following circuit:—battery, winding of relay Qr, brushes *d* of the tens, hundreds and thousands registers, contacts 1 of the quick operating but slow releasing relay Srr, contacts 2 of slow releasing relay Nr (which has not yet released its armatures), Err2—1 to ground. Relay Qr steps the tens switch to its normal position. Relay Kr is immediately energized over its right-hand winding via brushes *b* of the tens and units registers and contacts Mr1, Nr1, Err2—1 and closes the *b* wire of the fundamental circuit for the beginning of the units selection. Relay Pr now recloses the circuit of relay Rr which locks over the brushes *c* 60 of the registers, recloses the outstepping circuit and re-energizes relay Nr, causing the relapse of relays Srr and Qr.

When the fundamental circuit is opened at register circuit, relay 3Dcr is de-energized, opens the circuit of the power magnet 3PC at contacts 3Dcr2 and closes a circuit via contacts 3Dcr3, 3Fcr4 and Gcr3 for relay 3Gcr. Relay 3Gcr locks over contacts 3Gcr3—4, 3Ecr3 and 3Fcr6, closes a circuit over contacts 3Fcr6, 3Ecr3, 3Gcr3—4 and Xcr6 for relay Lcr, prepares a circuit for the test relay 3Hcr at contacts 3Gcr5 and closes a circuit via contacts 3Gcr6, 3Hcr4, Lcr3 and F1r6 for the final finder power magnet PF. The control switch stops on the last terminal set of the preceding group of ten lines the reason for this being that when the units selection is made the switch always makes one step. The contacts in level *f* of the control switch are connected to contacts *d* in the banks of the final finders and when the final finder reaches the marked terminal *d* the following circuit is completed for the test relay 3Hcr:—battery, winding of 3Hcr, contact 3Gcr5, brush *f* of control switch, terminal *d* and brush of final finder, contact F1r5 to ground. Relay 3Hcr opens the circuit of power magnet PF.

When the *b* wire of fundamental circuit is reclosed at the register circuit relay Dcr again energizes and closes a circuit for relay Ycr as follows:—battery, winding of relay Ycr, contacts Ycr1, 3Gcr2, 3Dcr2, off-normal contact N to ground: relay Ycr locks via contacts Ycr1—2, 3Ecr3 and 3Fcr6. Providing that the test relay 3Hcr has by this time energized a circuit is completed for relay Lcr via contacts 3Hcr2, Ycr5 and Mcr1. Relay Lcr grounds the *b* wire of the fundamental circuit at contacts Lcr1 and closes a circuit for the control switch power magnet 3PC via contacts Lcr2, 3Hcr3, 3Gcr6. Magnet 3PC advances the switch. When the brush on level *f* leaves the terminal on which it is standing relay 3Hcr relapses and opens the circuit of relay Lcr which removes the ground from the *b* wire of the fundamental circuit and recloses the circuit of the power magnet PF of the final finder which advances to its next position in which relay 3Hcr and Lcr again energize. In this manner reverting impulses for the units selection are sent back from the final control circuit to the register circuit, the final finder making one step for each impulse.

In the register circuit the reverting impulses are repeated by relay Qr to the units register magnet SW4. In position 10 of this register switch, relay Rr is unlocked. Relay Srr is energized and before relay Nr has time to relapse closes a circuit for relay Drr via contact Vr1, wipers *c* of all the register switches and contacts Srr1, Nr2 and Err2—1. Relay Drr locks up over contacts Drr5 and at contacts Drr6 opens the circuit of re-

lays U_r Fig. 9 and E_r , Fig. 2. Relay U_r opens the locking circuit of relay E_{rr} , Fig. 9, which in turn unlocks all the operated relays in the register circuit excepting relay D_{rr} . Relay D_{rr} also closes a circuit for relay Q_r via contact $D_{rr}3$, brushes e of all the register and interrupter contacts of magnet $SW4$. Relay Q_r closes a circuit to step the units register into its normal position. Relay Q_r releases immediately the units register steps out of position 10 but in the normal position is again energized over contacts $D_{rr}3$, the brushes e of the registers and contacts $D_{rr}5$. A check is made that all the 15 register switches are at normal and a circuit is then closed from ground via contacts Q_r2 all the brushes f and contacts $D_{rr}2$ for short-circuiting the lefthand winding of relay D_{rr} which releases. An exchange attendant by 20 throwing key RK can close a circuit for relay D_{rr} to restore the register circuit. Progress lamps A , B and C are connected to off-normal arcs d of the first three registers.

Returning now to the final control circuit, 25 when the fundamental circuit was finally opened in the register circuit relay $3Der$ de-energizes and the following circuit is closed for relay Mcr —battery, winding of relay Mcr , contacts Y_{cr4} , $3F_{cr4}$, $3D_{cr3}$, off-normal 30 contacts N to ground. Relay Mcr locks up via contacts $Mcr4$, $3E_{cr3}$, $3F_{cr6}$ disconnects relay L_{cr} at contacts $Mcr1$ before it has time to operate again and at contacts $Mcr5$ closes a circuit for relay X_{cr} via contacts P_{cr1} , 35 $3H_{cr1}$. Relay X_{cr} locks over contacts X_{cr4} , $3E_{cr3}$, $3F_{cr6}$ and at contacts X_{cr6} opens the circuit of relay L_{cr} which commences to release and on closing its contact L_{cr1} short-circuits the winding of relay Y_{cr} over contacts $Mcr5$: relay Y_{cr} releases. With relay Y_{cr} de-energized and relay X_{cr} energized a ground is connected to the lower winding of relay F_{2r} via off-normal contacts N , contacts $3D_{cr3}$, $3F_{cr4}$, Y_{cr3} , X_{cr3} , $F_{1r}4$; full battery 40 is also connected to the windings of relays F_{1r} and F_{3r} in parallel via contacts Y_{cr6} , X_{cr5} —this battery short-circuits relay $3F_{cr}$ which relapses. Relay F_{3r} operates and locks over its lower winding and contact 45 $F_{4r}1$ to the c wire.

If the wanted line is idle relay F_{2r} energizes in series with the cut-off relay thereof and locks over its upper winding to ground on the c wire: it is arranged that the time 50 for the operation of the relay F_{3r} Fig. 5 and the falling off of relay F_{1r} is sufficient to permit relay F_{2r} to operate on a free line. Ringing current is now supplied to the calling line from the ringing source via winding of relay F_{4r} , contacts $F_{3r}2$, $F_{2r}5$, called line, contacts $F_{2r}4$, $F_{3r}5$ to ground. Tell-tale ringing tone is applied to the calling line through the condenser MFR . When the called party answers relay F_{4r} operates and 55 unlocks relay F_{3r} . The called party is now

connected through to the line finder circuit Fig. 2 where relay S_{1r} energizes over the called party's loop and closes a circuit for relay F_r to ground at the contacts B_{r1} ; relay F_r locks to this ground via contacts G_{r7} 70 independently of relay S_{1r} and transfers the circuit of relay D_r to contacts S_{r2} of relay S_r via contacts $F_{r6}—5$. The calling and called parties are supplied with talking current over relays S_r and S_{1r} respectively. 75

If the called line is busy relay F_{2r} does not become energized and on the response of relay F_{3r} , busy tone from the source BT is transmitted to the calling line via contacts $F_{3r}3$, $F_{2r}6$ and the condenser MFR . 80

When relay F_{2r} or F_{3r} operates the locking circuit of relay F_{1r} is opened at contacts $F_{2r}1$ or $F_{3r}6$ and this relay relapses and disconnects the control circuit. The relapse of relay $3F_{cr}$ de-energizes relays $3G_{cr}$, $3H_{cr}$, X_{cr} and Mcr and a restoring circuit for the magnet $3PC$ is closed over off-normal contacts N , contacts $3D_{cr3}$, $3F_{cr3}$ and $3B_{cr1}$. 85

If the called party hangs up but not the calling party relay S_{1r} relapses and a circuit B_{r1} , $S_{1r}2$, F_{r3} is closed for a lamp GL over an alarm wire. 90

When the calling party hangs up relay S_r de-energizes and opens the circuits of relays D_r and B_r . Relay B_r releases slowly. Metering battery is connected to the c wire via contacts F_{r2} , G_{r5} and D_{r4} to operate the service meter SM Fig. 1. When relay B_r releases relay F_r de-energizes and disconnects the metering battery. Relay B_r removes ground from the c wire causing the relapse in turn of the switching relays J_{2r} , Fig. 3, $2J_{2r}$, Fig. 4, and F_{2r} at the group and final finders. These switches remain on the junction or line terminals with which they are in engagement. The opening of the c wire thus makes the circuit instantly available for a second connection. 105

Private branch exchange hunting

The level P of the final control finder is used for P. B. X. hunting and the front contacts Cor , Figs. 1 and 5 of the cut-off relays on all lines in a P. B. X. group except the last are connected to terminals on this level. 110

When the units selection is completed and relay Mcr Fig. 8 energizes, a circuit is prepared over contacts $Mcr3$, X_{cr1} for relay P_{cr} . Relay P_{cr} operates faster than the relay X_{cr} and if the wanted number is one of a P. B. X. group and is engaged, relay P_{cr} energizes disconnects relay X_{cr} at contacts P_{cr1} and closes a circuit over contacts P_{cr2} for the power magnet $3PC$ which advances the control switch a step onto the next contact set where relay $3H_{cr}$ falls off and closes the circuit for advancing the final finder to the next line in the P. B. X. group where relay $3H_{cr}$ again energizes. 115

If this line is also engaged, relay P_{cr} is again energized and the 120

control switch is advanced a further step. This action is continued until either a free line in the group is found or the last line is reached. On the last line the front contact of the cut-off relay is not connected to the P level and hunting is therefore definitely stopped. The last line is tested in exactly the same way as a single line and if it is engaged the busy tone is given to the calling 10 party.

Special service calls

As previously stated the register circuit is arranged to handle two digit special service calls for which the numbers 01, 02 etc. are reserved. If a first digit "0" is dialled, the thousands register switch is stepped to position 10 and before the relapse of relay Ir a circuit is closed via contacts Grr1 brush b 15 and contacts Dr6 for relay Tr which locks over contacts Tr5 to ground at contact Err2-1. The tens register cannot be set by a third digit as its circuit is opened at contact Tr6. At the end of the first and second 20 digits respectively, relays Jr and Lr are energized as in a normal call. The register circuit now controls selection at two group finder stages at the end of the second selection relay Dr being energized instead of relay Mr over the following circuit:—ground, contacts Err1-2, Nr2 and Srr1, brushes e 25 of thousands and hundreds register switches, contact Tr4, winding of relay Dr to battery. The energization of relay Dr causes 30 the register circuit to be released as previously described.

The call is directed over a regular group finder such as that shown in Fig. 3, (full line connections) and a special service second group finder to a local trunk to an operator's position as shown in Fig. 11. The special service second group finder is identical with that shown in Fig. 3 the connection marked X being removed and that 40 indicated in dotted lines being inserted. This differs from a regular second group finder in that a fifth brush is provided: its operation is substantially identical. When the trunk is engaged relay 1Ar, Fig. 11 operates over the 45 c wire and lights the calling lamp CL. The operator plugs in, the connection of earth to the sleeve contact closing a circuit over relay 1Br, Fig. 11, the e wipers of the special service second group finder and the regular 50 first group finder, and relays Er and Gr at the line finder link, Fig. 2. Relay 1Br Fig. 11 de-energizes relay 1Ar and extinguishes the calling lamp CL. Relay Gr Fig. 2 opens at contacts Gr7 the circuit of relay Dr which 55 disconnects the calling side current bridge. Relay Er disconnects the called side current bridge. The calling subscriber is now connected to the operator's position over a metallic circuit including contacts Gr1, Gr2. 60 Current for talking and other purposes is

supplied direct from the operator's cord circuit. Relays Sr and Cr are de-energized, whilst relay Gr at contacts Gr4 holds the calling line cut-off relay and at contacts Gr6-7 maintains relay Br energized independently of the calling party to transfer release control to the operator. If the operator should release before the calling subscriber, relay Gr de-energizes and the circuit of relay Dr is again closed and the current bridge connected to the calling line. Relay Sr therefore energizes and closes the original circuit for relay Br which holds the connection. The trunk circuit relay 1Ar, Fig. 11 is again energized and the calling 80 lamp CL lights to recall the operator.

Toll connections

Junctions from toll boards are associated with register circuits over relay groups as shown in Fig. 12. The same register circuits and group and final finders are used as for local calls. When the toll operator inserts a plug LP into the jack LJ of a function terminating in a group finder at 85 the automatic exchange, relay 2Ar, Fig. 12, is energized over the sleeve wire, connects relay 2Cr to the a and b wires of the junction at contacts 2Ar1, 2Ar3, grounds the c wire of the junction at contact 2Ar2, energizes the register finder common start relay Ar, Fig. 9, and marks the junction calling in the banks of the register finders over contact 2Ar4. Relay 2Cr closes an obvious circuit for relay 2Hr which locks to contact 100 2Ar2. A free register is attached and dialling tone connected to the junction in the usual way after which the toll operator depresses her dialling key DK and sends dial impulses from the dial DL which are received by relay 2Cr and retransmitted to the register circuit. After the first impulse is received by the register circuit the following circuit is closed:—Battery, contacts 2Ar4, winding of relay 2Er, Fig. 12, brush 110 c of register finder Fig. 9, windings of relays Ur and Vr brush b of thousands register switch in position 1, contacts Dr6 to ground. Relay 2Er Fig. 12 operates and connects relay 2Fr in parallel with relay 115 2Ar. Relay 2Fr locks to the sleeve wire, closes a parallel circuit over its right-hand winding for relay 2Ar, grounds the c wire and holds relay 2Hr at contacts 2Fr3. The resistance of relay 2Er is sufficiently low to 120 permit marginal relay Vr Fig. 9 to energize, this indicating to the register circuit that the call is from a toll operator. This indication takes the form of a reclosure of the fundamental circuit after the units selection. When the units register reaches position 10 relay Rr is unlocked as usual, relay Srr energizes and relay Nr relapses. With relay Vr energized in position 10 of the units register relay Wr energizes in place of re- 125 130

lay D_{rr} the circuit extending over contacts $Err1-2$, $Nr2$, $Sr1$, brushes c of all register switches, contacts $Vr2$ and $Wr1-2$. Relay Wr locks over its contacts $Wr2$ and closes the fundamental circuit over contact $Wr4$. When relay Nr relapses relay D_{rr} is energized over contacts $Wr3$, $Nr1$, $Err2-1$. Relay D_{rr} drives the units register to normal and restores all the register circuits as previously described. At the final finder control circuit this reclosure of the fundamental circuit causes the re-operation of relay $3Der$, Fig. 8 and this relay connects ground immediately to the winding 10 of relay $F2r$ via contacts $3Der2$, $Xcr2-3$, $F1r4$ before the slow-releasing relay Icr de-energizes and short-circuits relay Ycr to connect battery for the energization of relay $F3r$. Thus on a toll call the final finder 20 relay $F2r$ is connected up in advance of relay $F3r$. If the wanted line is free relay $F2r$ energizes and opens immediately the circuit of relay $F1r$ which disconnects the final finder from the control circuit. It is 25 clear that in this case relay $F3r$ cannot energize since its circuit is opened at contacts $F1r3$ and the connection to the called line is made without ringing current being applied from the final finder. If the wanted line is 30 busy relay $F2r$ does not energize, relay $F3r$ energizes on the relapse of relay Icr in the control circuit, and busy tone is connected and the control circuit disconnected in the normal manner. 35 The depression of a key BK , Fig. 12, at the toll board will light the busy lamps BL of all circuits engaged at the moment.

Toll offering and wire chief testing

40 As previously explained for toll offering and wire chief testing a special train of switches is taken into use in order that any subscriber's line even when engaged can be reached by the toll operator or the wire chief. In each group of 100 lines one special final finder is provided which differs from a regular final finder inasmuch as it is arranged to stop on the wanted line without testing or ringing. This final finder, the 45 circuits of which are shown in Fig. 14 is associated with the same control circuit as the regular final finders.

A special relay group Fig. 13 is connected to the jacks appearing on the toll board TB and the wire chief's test board WCD which is similar to the toll line circuit illustrated in Fig. 12 and becomes attached to a regular register circuit and causes the operation of the marginal relay Vr to indicate a toll call 55 in precisely the same manner. Relay $3Ar$, Fig. 13, closes circuits for busy lamps BL at both boards.

The call is extended under the control of a register circuit over special first and second group finders in normal manner to a

special final finder, Fig. 14. When a special final finder is equipped in the group of final finders served by the control circuit the dotted connections shown in Fig. 8 extending to contacts $1F1r6$ Fig. 14 are inserted in the circuit of relay Pcr , and the connection X is removed in order to prevent automatic hunting when the control finder is brought to the beginning of a P. B. X. group on being associated with a special final finder. When the control finder picks up the engaged final finder relays $1F1r$ and $1F2r$ are energized in parallel from the control circuit but relay $1F1r$ only operates and locks to the c wire. The final finder is controlled in normal manner for tens and units selection by the control circuit and on the completion of units selection on the reclosure of the fundamental circuit full battery is connected to the windings of relays $1F1r$ and $1F2r$. Relay $1F2r$ now operates, locks to the c wire over its lower winding, de-energizes relay $1F1r$ which disconnects the control circuit and extends the connection to the called line without the application of ringing current and irrespective of the condition of this line. The wire chief is provided with a key OTK for grounding a circuit extending over the e brushes of the first and second group finders and the c brush of the final finder to busy the called line: the circuit over the c brush of the final finder can only be closed in this manner.

False calls

When a register circuit is attached on the energization of relay Err Fig. 9, the following circuit is completed for the driving magnet TA of a timing switch T :—ground, contacts $Err1-2$, $Nr1$, $Kr1$ winding of magnet TA to battery. When the first digit is received this circuit is opened at contact $Kr1$ by the operation of relay Kr but, if no impulses are received before the expiration of a predetermined interval of say 30 seconds, the timing switch T advances its wiper 2 to the 100 contact 4 and closes the following circuit:—battery relays Hr , Ir , contacts $Jr7$, arc 4 and wiper 2 of the switch T , contacts $Jr1$, interrupter springs I of the magnet $SW1$ to ground. Relays Ir and Hr now energize and the relay Hr closes a circuit for the magnet $SW1$ which opens the circuit of relay Hr over its interrupter contacts: the relay Hr and magnet $SW1$ interact until the thousands register reaches position 10 in which relay Jr energizes and locks up and relay Tr is energized over contacts $Grr1$, brush b of the first register and contacts $Drr6$, and locks to contacts $Err2-1$. The timing switch magnet TA locks up over the following circuit:—battery magnet TA , arc 3, brush 1, contacts $Tr1-2$, $Lr7$, $Jr6$ to ground. The circuit of relays Hr , Ir is transferred over contacts $Tr7$ and the second register switch is stepped to position 10 in which relay Lr is energized 105 110 115 120 125 130

and opens the impulsing circuit to the register magnets. Relays H_r and I_r are held energized. Relay L_r opens the circuit of the timing switch magnet TA at contacts $Lr7$.
 5 In the meantime relay K_r has become energized over contacts $2Grr2$, $Jr6$ and selection proceeds, as if the digits 00 had been dialled and takes place in the same manner as a special service call.

10

All trunks busy

It will be remembered that relay Mr in the register circuit energizes and locks over the front contacts of relay Pr when a group finder commences its hunt for an idle trunk in a wanted group and is unlocked when the relay Pr de-energizes on the opening of the fundamental circuit when an idle trunk is seized. Relays N_r and R_r are de-energized 15 during hunting. Relay Mr at contacts $Mr1$ holds open the circuit of relay K_r . As long therefore as hunting continues relays K_r , N_r are unoperated and in this condition close a circuit via contacts $Kr1$, $Nr1$, $Err2-1$ for 20 the driving magnet TA of the time switch T and if after a predetermined interval, say 10 seconds, an idle trunk has not been picked up and the relay Mr unlocked and the relay K_r again operated, when the brush 2 of the 25 switch T engages contact 5 a circuit is closed for relay Frr . This circuit extends over contacts $Mr2$, $Jr1-2$, $Lr1$ to the interrupter contacts of the magnet SW2: if relay L_r is operated it extends over contacts $Lr1-2$ and 30 $Or1$ to the interrupter contacts of magnet SW3 and if relay Or is operated over contacts $Or2$ to interrupter contacts of the magnet SW4. Relay Frr locks to grounded contacts $Err1-2$ and connects busy tone over 35 lead B and contacts $Frr2$ to the tone transformer TC in place of dial tone, and by opening contacts $Frr1$ introduces the high-resistance winding of relay Ur in the circuit of relays Ur , Fig. 9 and Er , Fig. 2. Relay Er , 40 Fig. 2 now falls away and busy tone is sent to the calling party over the circuit previously described with reference to the transmission of dial tone. When the subscriber replaces his receiver the switches are released. 45 If after the expiry of a predetermined interval the register is not released when the brush 2 of the switch T engages contact 6 an alarm lamp GL is lighted.

55

Incomplete calls

The circuit for the timing switch magnet TA described in the last paragraph will be completed whenever the set up has progressed as far as the recorded digits but immediately the next digit is recorded relay K_r operates and opens the circuit of the magnet TA. If therefore the calling party delays dialling after any digit the alarm lamp GL will be lighted over the alarm wire and 60 brush 2 after a predetermined interval.

Premature release

If the calling party releases prematurely before any dialling impulses have been sent but after a register circuit has been attached the relapse of relay Sr Fig. 2 causes the response of relay H_r Fig. 9 which advances the thousands register a step. Relays Br , Dr , and Cr , Fig. 2 are also unlocked and relay Crr Fig. 9 de-energized. In position 1 of the thousands register the usual circuit is completed for relays Ur , Fig. 9 and Er , Fig. 2 but this circuit is opened by the relapse of relay Dr , Fig. 2. Relay Err , Fig. 9 therefore relapses and relays I_r , H_r are de-energized. In position 1 of the thousands register relays J_r , Grr are energized and a circuit is closed for relay Drr via contacts $Grr3$ and $Ur1$. Relay Drr locks up and the register circuit is restored in known manner.

If the calling party releases prematurely after dialling part of the wanted number, relays Sr , Br , Dr Fig. 2 de-energize, the circuit of relays F_r , Fig. 2 and Ur , Fig. 9 is opened, relay Err Fig. 9 is unlocked and during the relapse of slow release relay Grr the above described circuit is closed for release relay Drr .

Incoming calls from distant exchanges

Two-wire junctions from distant exchanges terminate in relay groups as shown in Figure 10 attached to incoming group finders similar to the finder illustrated in Figure 4. When, as previously described, at the end of the first selection the a wire is connected to battery in the register circuit over contacts $Kr3$ and the b wire to earth over contacts $Kr4$, winding of relay Pr , contacts $Err6$, the high resistance supervisory relay Sbr which is normally bridged across the junction in series with the low resistance supervisory relay Sar at the relay group Figure 10, energizes: relay Sar remains unoperated. Relay Sbr closes a circuit via contacts $Br1$ for relay Ar which locks over contacts $Cr1$, closes a circuit for relay Br over contacts $Ar7$, opens the bridge over relay Sbr and completes a metallic through connection over the a and b wires and contacts $Ar1-2$ and $Ar4$ to the incoming group finder. Relay Br feeds holding ground forward over the third wire. The relay Cr is now inserted in series in the a wire and is shunted by the resistance R and one of the talking condensers. This relay Cr is polarized and does not operate at this time nor during the setting up of the connection which takes place in the usual manner under the control of the register circuit.

At the end of a selection or on a premature release when relay Drr Fig. 9 energizes in the register circuit and brings about the release of the register circuit, a potential of opposite polarity is connected to the a wire

for a short interval over contacts $G_{77}5$ and $D_{77}4$ during the relapse of the slow release relay G_{77} . Relay Cr which always finds a ground over the start relay A_{cr} of the control circuit of a second group or final finder now responds and unlocks relay A_r which cannot re-energize during the slow release period of relay Br . The high resistance bridge relay S_{br} now becomes energized to battery and earth at the calling line cord circuit over a relay S_{1r} (see Fig. 2) and a retard and holds relay Br over contacts $Br2$ Fig. 10 and S_{br1} . Relay Br holds over its left-hand non-inductive high resistance winding in series with its right-hand winding to economize in current and to render this relay relatively quick to release at the end of conversation. On the reply of the called party talking current is fed over a retard and the supervisory relay S_{cr} which energizes and short circuits the high resistance supervisory relay S_{br} causing the response of the low resistance supervisory relay S_{ar} and the cord circuit relay S_{1r} . Relay S_{ar} holds relay Br whilst relay S_{1r} operates and initiates the operations described for a local call. In the case of a premature release, the relapse of relay Br Fig. 2 brings about the release of the register circuits, as previously described. The relay J_{2r} Fig. 3 of first group finders is made slow to release in order to give sufficient time for the impulse of opposite polarity, previously referred to, to be sent to the incoming relay group and for the relay Cr thereto to respond. On the response of relay Cr , however, and the release of relay A_r , no circuit is found for relay S_{br} so that the relay Br Fig. 10 releases and initiates the release of the succeeding switches. It will be seen that no means is provided for busying the two-wire junctions when the control switch associated with the finder at the incoming end is busy. This does not materially affect the working of the system since the average time a control circuit is in actual use is very small. If the corresponding control circuit is in use when a junction is seized, therefore, only a very short interval will elapse before it falls free and is available for extending the connection over the junction in question. A jack OJ is provided for disabling the junction.

What is claimed is:

1. A telephone system comprising a plurality of final selectors having common control circuits adapted to be associated therewith, said selectors having access to subscribers' lines and to toll lines, and said control circuits comprising means adapted to control the operation of the final selector with which it is associated to effect the connection of said switch with either a toll line or a subscriber's line.

2. A telephone system comprising a plurality of selectors, common control circuits

therefor, said selectors being adapted to be used in completing calls to a subscriber's line or to a toll line, and means comprised within said control circuits for causing the application of ringing current to the selected line in the event such line is a subscriber's line.

3. A system according to claim 2 wherein in the event the selected line is a toll line the connection is adapted to be completed without the application of ringing current to said toll line.

4. A telephone system comprising a plurality of selectors, one of said selectors being adapted to extend calls of one type and one of said selectors being adapted to extend calls of another type, and common control circuits for said selectors adapted to control the operation thereof in effecting either type of call.

5. A system according to claim 1 wherein said means is adapted to be operated in response to a signal received over the talking circuit.

6. A system according to claim 1 comprising a registering and controlling mechanism, said mechanism being adapted to control the extension of a call to a subscriber's line and to a toll line.

7. A telephone system comprising a plurality of selectors, common control circuits therefor, a registering and controlling mechanism adapted to record impulses, representing the designation of subscribers' lines and toll lines over different paths, said mechanism being adapted to cause a discrimination to be exercised in said common control circuits in accordance with the path over which said impulses are received.

8. A telephone system comprising selector switches, common control circuits therefor, a registering and controlling mechanism adapted to record received impulses and to control one of said selectors by revertive impulses sent back to said mechanism by said selector over a circuit extending therebetween, the operation of the selector being also controlled by means adapted to open said circuit on the termination of the selective operation of said selector.

9. A system in accordance with claim 2 comprising a toll operator's position and wherein said position is provided with means for applying ringing current to a toll line.

10. A system according to claim 1 wherein a final selector is provided with a relay, said relay being adapted to be operated simultaneously with the testing of a subscriber's line.

11. A system according to claim 1 wherein the operation of a relay in a final selector is adapted to be delayed in the event the wanted line is a toll line until the selected toll line has been tested.

12. A system according to claim 4 wherein the selector adapted to extend calls of one type is adapted to engage a line without test-

ing the condition thereof or applying ringing current thereto.

13. A system according to claim 1 wherein a registering and controlling mechanism adapted to control the extension of a call to a subscriber's line and to a toll line comprises a marginally adjusted relay, said relay being adapted to remain unoperated when said mechanism is taken into use for extending a call to a subscriber's line and to be operated when said mechanism is taken into use for extending a call to a toll line whereby a discrimination is subsequently exercised to prevent the automatic application of ringing current to the selected line.

14. A system according to claim 1 wherein said selectors are of the single motion power driven type.

15. A telephone system comprising a plurality of selectors for setting up connections for one type of calls and a plurality of selectors for setting up connections for calls of another type and common control circuits adapted to be associated with and control the operation of any one of said selectors.

16. A telephone system comprising subscribers' lines, a wire chief's position, a selector switch adapted for use in setting up a connection between any two of said subscribers' lines, a selector switch adapted for use in setting up a connection between said position and a subscriber's line, and a control circuit common to said selectors for controlling their selective operations.

17. In witness whereof we hereunto subscribe our names this 27 day of February, 1930 and 3rd day of February, 1930.

GERALD DEAKIN.

EDOUARD FRUM,

18. Legal Administrator of the Estate of Lipa Polinkowsky, Deceased.
